UNITED STATES PATENT OFFICE.

MAZIE T. WATERS, OF WACO, TEXAS.

DESIGN FOR A CHILD'S SOAP-BUBBLE APRON.

61,023.

Specification for Design.

Patented May 30, 1922.

Application filed February 9, 1921. Serial No. 443,729. Term of patent 3½ years.

To all whom it may concern:

Be it known that I, MAZIE T. WATERS, a citizen of the United States, residing at Waco, in the county of McLennan and State of Texas, have invented a new, original, and ornamental Design for a Child's Soap-Bubble Apron, of which the following is a specification, reference being had to the accompanying drawing, forming part thereof.

The figure is a plan view of an apron, showing my new design.

I claim:

The ornamental design for a child's soap bubble apron, as shown.
